UNITED STATES PATENT OFFICE.

THOMAS E. COLLINS, OF CHICAGO, ILLINOIS.

FIRE-DOOR.

No. 926,978.

Specification of Letters Patent.

Patented July 6, 1909.

Application filed May 18, 1908. Serial No. 433,391.

To all whom it may concern:

Be it known that I, THOMAS E. COLLINS, a citizen of the United States, residing at Chicago, in the county of Cook and State of Illinois, have invented a new and useful Improvement in Fire-Doors, of which the following is a specification.

My invention relates particularly to rolling shutters employed as fire-doors; and my primary object is to provide means simplifying the construction of such doors as well as improved means for effecting the automatic closing in the event of fire.

My improvements are illustrated in the preferred embodiment in the accompanying drawings, in which—

Figure 1 represents a section of a fire-wall having a door constructed in accordance with my improvements; Fig. 2, an enlarged broken sectional view, showing the drum which supports the shutter and the gears connected therewith; Fig. 3, a section taken as indicated at line 3 of Fig. 2; Fig. 4, a broken perspective view of the casing or hood in which the drum and shutter are normally housed, this view showing also a portion of the means for locking the balancing spring under a given tension; Fig. 5, an inner perspective view of a gear which has been removed from the spindle or stud appearing near the lower portion of Fig. 4; Fig. 6, a broken elevational view of the shutter employed; Fig. 7, a section of the shutter taken as indicated at line 7 of Fig. 8, the section 35 being on a larger scale than Fig. 8, however; Fig. 8, a section taken as indicated at line 8 of Fig. 6; and Fig. 9, a perspective view of a clip or runner which is shown applied to the end-portions of alternate slats or bars 40 of the shutter in Fig. 6.

In the construction illustrated, A represents a fire-wall having a door opening A¹ equipped with the usual Z-bar guides A²; B, a shutter adapted to work in said guides; C, a drum with which the upper end of the shutter is connected in any desired manner (not shown); C¹, C², a pair of brackets supported by the wall above the door-opening and upon which is mounted a hood C³ in which the drum and shutter are normally housed; C⁴, a shaft journaled in the bracket C² and in the bearing with which the interior of the drum C is provided; C⁵, a counter-balancing spring having one end connected 50 with the drum and the other end connected with the shaft C⁴; D, a pinion fixedly secured

on the projecting end of the shaft C⁴; D¹, a gear meshing with the pinion D and journaled on a stub-shaft D² projecting from the bracket C²; D³, a bell-crank lever supported on a pivot projecting from the bracket C² and equipped with teeth normally engaging the teeth of the gear D¹; D⁴, bell-crank lever normally holding the lever D³ in the gear-locking position; and D⁵, a wire connecting the lever D⁴ with a stationary part, said wire being provided with a fusible link D⁶, which is ordinarily located above the vertical central line of the door.

The guides A² for the shutter may be of any suitable construction. As has been indicated, Z-bars are commonly employed for forming such guides. The shutter B comprises slats 1 connected by hinges 2. In common practice, the slats or bars of the shutter are formed of sheet-metal, each slat having its longitudinal edge-portions curved to form hinged members. The hinge members slide longitudinally into each other, thus connecting the bars together. I provide improved end-clips 3 for maintaining the slats or bars of the shutter in proper relation after they have been connected in the usual manner by telescoping the hinge parts with relation to each other. Each clip 3 comprises a shank 4 and a head 5 which are formed integral with each other by stamping from sheet-metal. This is accomplished by bending the part 5 at right angles to the part 4. The part 5 thus extends transversely with relation to the shank 4 and in a plane at right angles to the plane of the shank 4. The end portions 6 of the part 5 extend beyond the lateral edges 7 of the shank, so that when the shank is secured to one slat the projecting portions 6 will serve to lock the adjacent slats against longitudinal movement. By employing a clip at each end of alternate slats, the slats are all properly secured against longitudinal movement with relation to each other. The projections or lugs 6 are struck or dished outwardly, as indicated at 8, thereby providing small bosses or bearings adapted to engage the walls 9 of the guides A².

The drum C is provided at one end with a stub-shaft 10 which is journaled in a bearing in the bracket C². The inner end of the shaft C⁴ is journaled in a bearing 11 with which the drum C is provided interiorly. The bearing 11 is rigidly secured to the drum, and one end of the spring C⁵ is connected with said bearing. The other end of the

spring is secured to a member 12, which is fixed on the shaft C⁴. The shaft projects through a bearing 13 with which the drum is provided near one end and through a bearing with which the bracket C² is provided, the pinion D being secured on the shaft outside the bracket C². The projecting end of the shaft is equipped with an angular member 14 to which a crank may be applied for the purpose of applying tension to the spring C⁵. The gear D¹ is equipped on its inner side with a lug 15 and the bracket C² is equipped on its outer side with a lug or stop 16 which will be encountered by the lug or stop 15 when the gear D¹ rotates in the direction indicated by the arrow in Fig. 3, which will occur when the gear-locking lever D³ is released, owing to the fusing of the link D⁶.

The lever D² is supported on a pivot 17 which projects from the outer surface of the bracket C². The short arm of the lever D² normally stands in a substantially vertical position and is equipped with teeth 18 adapted to engage the teeth of the gear-wheel D¹. The lever D² is supported on a pivot 19 which is perpendicular to the pivot 17, the short arm of the lever extending beneath the long arm of the lever D³. The long arm of the lever D⁴ stands substantially vertical and has one end of the wire D⁵ connected therewith, the other end of the wire being connected with a lug 20 projecting forwardly from the hood C³.

The spring C⁵ is, in practice, put under sufficient tension to serve as a counter-balance for the shutter, regardless of the distance that the shutter is drawn down from the drum. The adjustment is such that when the gear D¹ is released from the lever D² the tension upon the spring will be partially relieved, owing to the fact that the gear D¹ will rotate until its lug 15 encounters the lug 16 on the bracket C², during which time the shaft C⁴ will rotate several times in a direction to partially relieve the tension upon the spring C⁵. Owing to the partial relief of the

tension upon the spring, the shutter will fall under its own weight and close the door-opening. At the same time, the tension upon the spring will be sufficient to prevent undue shock and avoid injury to the door, regardless of the size and weight of the door.

The foregoing detailed description has been given for clearness of understanding only, and no undue limitation is to be understood therefrom.

What I regard as new, and desire to secure by Letters Patent, is—

1. In a construction of the character set forth, the combination of a shutter, a drum connected therewith, a spring in said drum and connected therewith, a shaft extending into said drum and connected with said spring, a pinion secured on said shaft, a gear meshing with said pinion and equipped with a stop, a stationary stop co-acting with said first-named stop, a gear-locking lever, and holding means for said lever provided with a fusible connection.

2. In a construction of the character set forth, the combination of a pair of brackets, a drum equipped at one end with a shaft journaled in one of said brackets, a shaft journaled in the other bracket and extending into said drum, a spring connected with said drum and with said second-named shaft, a pinion secured on the outer end of said second-named shaft, a gear meshing with said pinion and equipped on its inner side with a stop, a stop projecting from the adjacent bracket and co-acting with said first-named stop, a gear-locking lever, a pivot therefor projecting from the adjacent bracket, a second lever, a pivot therefor extending substantially perpendicular to said first-named pivot, and a fusible link connected with said second-named lever.

THOMAS E. COLLINS.

In presence of—

RALPH A. SCHAEFER,
Wm. P. OTT.
